REFLECTOR FOR PEDESTRIANS

Lane Soutar, Hickory, N.C.

Application May 2, 1958, Serial No. 50,729

Term of patent 14 years

(Cl. D72—1)

Fig-1

Fig-2

Fig-3

Figure 1 is a front view of a reflector for pedestrians embodying my new design;

Figure 2 is a side elevational view of the reflector for pedestrians;

Figure 3 is an enlarged fragmentary view of the reflector for pedestrians looking at the reflecting surface of Figure 1.

The back of the reflector for pedestrians is substantially plain.

I claim:

The ornamental design for a reflector for pedestrians, as shown and described.
